UNITED STATES PATENT OFFICE.

GEORGE H. CLARK, OF PARIS, MAINE.

AUTOMATIC TRAIN-STOPPING DEVICE.

1,193,122.

Specification of Letters Patent.

Patented Aug. 1, 1916.

Application filed January 5, 1914. Serial No. 810,298.

To all whom it may concern:

Be it known that I, GEORGE H. CLARK, a citizen of the United States, and resident of Paris, in the county of Oxford and State of Maine, have invented new and useful Improvements in Automatic Train-Stopping Devices, of which the following is a specification.

This invention relates to automatic train stopping devices, and more particularly to means for normally holding the air brake system of a railroad train inactive and for automatically applying the brakes if and when the engineer attempts to pass a signal set against the train, or in "stop" position. I am aware that many devices have been proposed for this purpose, but so far as I am informed none has gone into general or successful use, although the need for such a device is fully recognized and the demand therefor has long been insistent.

It is the object of this invention to provide an automatic train stopping device which shall be simple, with a minimum of working parts, certain and efficient in operation, and adapted for use under all practical conditions of railway signal practice.

Referring to the drawings, Figure 1 is a diagrammatic view of a part of a railroad line embodying my improved system; Fig. 2 is a diagrammatic view of the equipment on the engine or other unit; Figs. 3 and 4 are sectional views of a control valve of the mechanism shown in Fig. 2; and Fig. 5 is a section on line 5—5 of Fig. 4.

1 is a casing mounted in any suitable manner upon the lower part of the engine, as shown in Fig. 1. Secured in said casing and projecting therefrom is an armature 2 having a movable member 3 provided with a stop 4, (see Fig. 3) normally held in elevated position by a spring 5. Extending laterally from said casing 1 is a valve casting 6 provided with a valve seat 7 for the valve 8, and having a port in front of said valve seat in which is secured an end of the train line pipe 9 and a port behind said valve seat in which is secured the pipe 10, in effect a continuation of said train line pipe 9, and open to the atmosphere. Within said casing 1 is a horizontally disposed rod 11 having a socketed head 11^a, in which is slidably mounted the valve stem 12. A spring 13 surrounds said stem 12 and is normally held under compression between said head 11^a and a stop 12^a fast to said stem.

Pivotedly secured to said casing 1 and connected with said rod 11 by a slot and pin connection, is a latch 14 having a catch 14^a which normally engages the stop 4 on the movable armature member 3 to lock said latch. When said latch 14 is in its normal locked position shown in Fig. 3, the spring 13 is compressed, and the valve 8 is held and locked upon its seat 7, closing the train line pipe 9.

Upon the end of the rod 11 opposite to that carrying the head 11^a, is a plunger 15 adapted to reciprocate in a cylinder 16 formed in said casing 1. The said cylinder 16 has a small port 17 open to the atmosphere and an opening in its end in which is secured an end of the air reservoir pipe 18.

Referring now to Figs. 4 and 5; 19 is a frame located in the engine cab, in which is a valve casing 20 with which the train line pipe 9 and air reservoir pipe 18 communicate. In said valve casing is a control valve 21 having ports 22 and 22^a disposed at right angles to each other and adapted to control the passage of air through said pipes 9 and 18. As shown in the drawings, the said valve 21 is in its normal position, the train line pipe 9 being open and the air reservoir pipe 18 closed. In said frame 19 there is rotatably mounted a threaded rod 23 having a wheel 24 for manually operating the same. To the projecting stem of said valve 21 there is secured a lever 25 connected by a link 26 with a nut 27 upon the rod 23. The rotation of said rod 23 causes the nut 27 to move along said rod, this movement being communicated to the valve stem by the link 26 and lever 25 to rotate the control valve 21 for the purpose presently to be described.

By reference to Fig. 2 it will be seen that the pipe 10 communicates with a valve casting 28 provided with a valve 29 having ports 30, so that said pipe 10, which is in effect a continuation of the train line pipe 9, is always open to the atmosphere. The stem 31 of the valve 29 projects above the valve casing and has a pin and slot connection with a pivoted lever 32. This lever 32 is located in the path of movement of the usual reverse lever 33, which has a stud or projection 34 adapted to lift and hold the lever 33 and valve 29 when the reverse lever is moved along the quadrant 35 in the usual manner as the engine gains speed.

The signal (Fig. 1) comprises a track magnet 36 located between the rails and adapted to be energized in any suitable manner when the signal is set at "stop." 5 If now the engineer fails to observe or disregards the "stop" signal and runs by, as soon as the armature 2 carried by the engine enters the field of the track magnet 36, the movable members 3, in order to include the 10 maximum of lines of force, moves into contact with the adjacent portions of the armature, closing the magnetic circuit as completely as possible; this movement unlocks latch 14 which swings upward, urged by 15 spring 13, moves rod 11 to the right as viewed in the drawings, and unlocks the valve 8 so that the pressure of air in the train line pipe 9 lifts said valve from its seat and rushing out through the pipe 10 20 sets the air brakes.

It will be readily understood that if the train is running slowly at the time it passes the "stop" signal, a service application of the brakes will be sufficient quickly to bring 25 the train to a standstill. If, upon the other hand, the train is running at high speed, there must be an emergency application of the brakes in order to stop the train within the shortest possible distance. It is to meet 30 these conditions that the valve 29 and its operating lever 32 are provided. When the engine is running slowly the valve 29 is seated, as shown in Fig. 2, and the ports 30 therein are of proper size to govern the rush 35 of air from the train line pipe 9 through the pipe 10 to effect a service application of the brakes. If, however, the train is running at speed, the reverse lever 33 will, according 40 to the well known practice, have been drawn back toward the center upon the quadrant 35, thus lifting the lever 32 so that the valve 29 is lifted and held off its seat by the stud or projection 34. With the valve 29 off its 45 seat, the rush of air from the train line pipe 9 through the pipe 10 is unobstructed and an emergency application of the brakes is obtained.

To reset the apparatus, the threaded rod 23 (Figs. 4, 5), is rotated, causing the nut 27 50 to move along said rod, this turning movement being communicated to the valve stem by the link 26 and lever 25 to rotate the control valve 21. The rotation of the control valve is continued until it has turned 90° 55 from its normal position shown in Fig. 4, thus closing the train line pipe 9 and opening the air reservoir pipe 18, permitting air to be pumped through said pipe into the cylinder 16 behind the plunger 15 (Fig. 3), 60 causing said plunger to move to the left as viewed in the drawings. As said plunger is thus moved in response to the air pressure, the rod 11 to which it is secured moves with it, compressing the spring 13, swinging the 65 latch 14 downward, and locking it with the

movable armature member 3, thus reseating the valve 8 and restoring the apparatus to normal, inactive locked position. When the apparatus has been thus restored to normal position the rod 23 is again rotated in reverse direction and the valve restored to its normal position shown in Figs. 4 and 5, so that the train line pipe 9 is opened and the air reservoir pipe 18, closed. 70

The port 17 of the cylinder 16 is smaller 75 than the area of the air reservoir pipe 18 and permits the pressure in the cylinder to drop after the valve 21 is returned to normal position. It should be observed that said port 17 is large enough to prevent the air brake 80 system from operating unless the valve 8 is closed, for its discharge capacity is greater than the pump capacity, so that if held open long enough it permits the pressure in the reservoir to drop. 85

It will, I believe, be apparent that an automatic train stop constructed in accordance with my invention is simple and without complicated mechanism likely to get out of order. All the moving parts are entirely 90 covered and thus protected against dirt and water, yet they are susceptible of ready inspection. There is no electrical apparatus carried upon the train yet all the defects incident to purely mechanical train stops are 95 eliminated. The track arrangements are simple, keep themselves clear of ice, snow or water, and have no moving parts to be tampered with or likely to get out of order. The train is readily and safely stopped by a service 100 application of the brakes if the train is running slowly and by an emergency application if it is traveling at speed. When the reason for the setting of the signal has been ascertained and the engineer receives 105 his orders to go on, he is enabled readily to reset the device without leaving the cab. It will be observed that none of the valves in the above described apparatus require any packing; except in the case of valve 8, tight 110 fitting is not requisite since leakage at other points does not materially affect the operation. 115

I claim:

1. The combination with the brake system 115 of a railroad train, of means carried by said train adapted normally to hold said brake system inactive, comprising an armature having a movable member, a spring for holding said movable member in normal position, a valve adapted normally to close the train line pipe, a seat and a stem for said valve, a rod having a socketed head in which said valve stem is slidably mounted, a spring normally held under compression surrounding 120 said stem, a pivoted latch, a connection between said latch and said rod, said latch adapted normally to engage said movable member of said armature to lock said valve on its seat, a magnetic field adjacent to the 125 180

track adapted when said armature enters said field to actuate said movable member to release said latch and unlock said valve, whereby said train line pipe is opened to apply the brakes.

2. The combination with the brake system of a railroad train, of means carried by said train adapted normally to hold said brake system inactive, comprising an armature 10 having a movable member, a spring for holding said movable member in normal position, a valve adapted normally to close the train line pipe, a seat and a stem for said valve, a rod having a socketed head in which said valve stem is slidably mounted, a spring normally held under compression surrounding said stem, a pivoted latch, a connection between said latch and said rod, said latch adapted normally to engage said movable 20 member of said armature to lock said valve on its seat, a magnetic field adjacent to the track adapted when said armature enters said field to actuate said movable member to release said latch and unlock said valve, 25 whereby said train line pipe is opened to apply the brakes, and means carried by the train adapted to reset said brake-system-holding means in normal position.

3. The combination with the brake system of a railroad train, of means carried by said train adapted normally to hold said brake system inactive, comprising an armature having a movable member, a valve normally closing the train line pipe, a latch 35 connected with said valve and engaging said movable member of said armature to lock said valve in closed position, a magnetic field adjacent to the track adapted to actuate said movable member of said armature 40 when it enters said field to unlock said valve, open said train line pipe and apply the brakes, and manually controlled means carried by said train adapted to reset said brake-system-holding means in normal position, 45 comprising a cylinder with which the reservoir pipe connects, a port and a plunger in said cylinder, a connection between said plunger and said normally closed train line pipe valve and said latch, and means adapted to permit the air to enter said cylinder through said reservoir pipe whereby said plunger is moved, returning said valve to its seat and locking it thereon.

4. The combination with the brake system of a railroad train, of means carried by said train adapted normally to hold said brake system inactive, comprising an armature having a movable member, a valve normally closing the train line pipe, a latch 55 connected with said valve and engaging said movable member of said armature to lock said valve in closed position, a magnetic field adjacent to the track adapted to actu-

ate said movable member of said armature when it enters said field to unlock said valve, 65 open said train line pipe and apply the brakes, and manually controlled means carried by said train adapted to reset said brake system holding means in normal position, 70 comprising a cylinder with which the reservoir pipe connects, a port and a plunger in said cylinder, a connection between said plunger and said normally closed train line pipe valve and said latch, means comprising a control valve and means to operate the 75 same, adapted to permit the air to enter said cylinder through said reservoir pipe to move said plunger, whereby said valve is returned to its seat and locked in normal position by said latch.

5. The combination with a brake system of a railroad train, of means comprising an armature carried by said train adapted normally to hold said brake system inactive, and a magnetic field located adjacent to the 85 track adapted to actuate said armature when it enters said magnetic field to open the train line pipe, a normally seated valve located in said pipe and having ports of sufficient size to permit a service application of the brakes 90 when said train line pipe is opened, and means to lift and hold said valve off its seat to permit an emergency application of said brakes, comprising a movable reverse lever having a projection, a pivoted lever 95 lying in the path of movement of said reverse lever and adapted to be lifted and held by said projection, and a valve stem connecting said pivoted lever and said valve.

6. The combination with a railway train 100 brake system, of means carried by a vehicle of the train, comprising an armature normally interrupted by an air gap and having a movable part adapted to close said air gap, connections controlled by the said movable 105 armature part to operate the brake system by opening the train pipe, a normally seated valve located in said train pipe and having ports of sufficient size to permit a service application of the brakes when said train 110 line pipe is opened, and means to lift and hold said valve off its seat to permit an emergency application of said brakes, comprising a movable reverse lever having a projection, a pivoted lever lying in the path of movement of said reverse lever and adapted to be 115 lifted and held by said projection, and a valve stem adapted to move said pivoted lever in said valve.

Signed by me at Boston, Massachusetts, 120 this 30th day of December, 1913.

GEORGE H. CLARK.
